APPARATUS FOR PREVENTING WELL FIRES
John W. Marx, Bartlesville, Okla., assignor to Phillips Petroleum Company, a corporation of Delaware
Filed Nov. 20, 1963, Ser. No. 325,121
8 Claims. (Cl. 166—53)

This is a continuation-in-part application of applications Serial No. 732,730, filed May 2, 1958, and Serial No. 857,629, filed December 7, 1959, now U.S. Patent No. 3,135,324. Application Serial No. 732,730 is a continuation-in-part of application Serial No. 526,388, filed August 4, 1955, and now abandoned.

This invention relates to apparatus for preventing borehole fires during in situ combustion of a carbonaceous stratum to recover oil therefrom.

In situ combustion in the recovery of hydrocarbons from underground strata containing carbonaceous material is becoming more prevalent in the petroleum industry. In this technique of production, combustion is initiated in the carbonaceous stratum and the resulting combustion zone is caused to move thru the stratum by either inverse or direct air drive, whereby the heat of combustion of a substantial proportion of the hydrocarbon in the stratum drives out and usually upgrades a substantial proportion of the unburned hydrocarbon material.

The ignition of carbonaceous material in a stratum around a borehole therein followed by injection of air thru the ignition borehole and recovery of product hydrocarbons and combustion gas thru another borehole in the stratum is a direct air drive process for effecting in situ combustion and recovery of hydrocarbons from the stratum. In this type of operation the stratum frequently plugs in front of the combustion zone because a heavy viscous liquid bank of hydrocarbon collects in the stratum in advance of the combustion zone which prevents movement of air to the combustion process. To overcome this difficulty and to permit the continued progress of the combustion zone thru the stratum, inverse air injection has been resorted to. By this technique, a combustion zone is established around an ignition borehole by any suitable means and air is fed thru the stratum to the combustion zone from one or more surrounding boreholes.

In the process of recovering oil by underground combustion, it is generally necessary to inject air into the porous, permeable, oil-bearing rock for extended periods. Field test results to date indicate that spontaneous ignition may occur during such air injection at high pressures. For example, a petroleum company recently conducted an underground combustion field test in the South Belridge field, Kern County, California, in which premature spontaneous ignition occurred at the central injection well in a direct injection system. Subsequent performance indicated that this ignition was limited to the upper portion of the pay zone, and that this partial ignition detracted from the field performance in that it reduced the volumetric sweep efficiency of the direct drive front.

Spontaneous ignition at air injection wells in any counterflow combustion process would have even worse effects as it would force immediate shutdown and possibly result in loss of a whole well pattern since there would be burning at the wrong places in the pattern.

In field tests in which hydrocarbons were recovered by in situ combustion in a tar sand by inverse air injection it was found that a material proportion of the injected air by-passed the combustion front and appeared in the production borehole along with produced hydrocarbons. Even in the ignited zones, air is believed to by-pass the fire front because of thermal fracturing which provides some channeling therethru. The by-passed oxygen mixes with the combustible products from the burning zones

2

and appears in the production well which is generally above the ignition temperature of the hydrocarbon-oxygen mixture when this happens, and field tests to date indicate, as a rule rather than the exception, that the mixture burns in the production borehole and production tubing unless suitable precautions are taken. Temperatures in excess of 2500° F. have been frequently observed in a production borehole from this cause. This temperature has been more than sufficient to melt downhole equipment on several occasions. Furthermore, if the by-passed oxygen quantity is large, it may consume the entire product, thereby rendering the process entirely useless. In addition, serious personnel hazards are created.

This invention is concerned with apparatus for preventing undesirable or premature spontaneous combustion in either a direct or inverse drive in situ combustion process during injection of combustion-supporting, oxygen-containing gas thru an injection well in the stratum being produced. It is also concerned with apparatus for preventing fire in a production well in either a direct or a reverse drive process.

Accordingly, it is an object of the invention to provide apparatus for preventing fire in a well associated with an in situ combustion process. Another object is to provide a means for maintaining the temperature of a stratum adjacent an injection borehole, during air injection, below ignition temperature at ambient conditions. It is also an object of the invention to provide apparatus for controlling and regulating borehole temperatures. A further object is to provide apparatus for preventing combustion of produced gases in a production well during either direct or inverse in situ combustion. Other objects of the invention will become apparent upon consideration of the accompanying disclosure.

A broad aspect of the invention comprises apparatus for sensing the temperature either in an injection borehole within the stratum to be produced while injecting air or other combustion-supporting gas or in a production well during movement of a combustion front toward same, and, as the temperature approaches the ignition temperature of hydrocarbon material in the borehole or in the wall of the borehole, injecting into the borehole a fine dispersion of water, such as a water aerosol, in sufficient quantity or at a sufficient rate to maintain the temperature at a safe margin below the ignition temperature. The apparatus comprises, in combination with a cased well extending into the stratum being or to be produced, a temperature sensing device in the well within the stratum, a supply of water under sufficient pressure for injection and dispersion, a line leading from the water supply into the well, a valve in this line, and means responsive to the sensed temperature of said sensing device in operative control of said valve.

A more complete understanding of the invention may be had by reference to the accompanying schematic drawing of which FIGURE 1 is an elevation thru a section of stratum showing an arrangement of apparatus in accordance with the invention; FIGURE 2 is an elevation in partial section showing another embodiment of the water dispersion means; FIGURE 3 is a view similar to FIGURE 2, showing another embodiment of the water injection means; and FIGURE 4 is a similar elevation showing another arrangement of apparatus in accordance with the invention.

Referring to FIGURE 1, a carbonaceous stratum 10, such as an oil sand, is penetrated by a well or borehole 12 provided with a casing 14 extending to the stratum, and a wellhead 16. In one embodiment a thermocouple 18 is suspended on a cable 20, including an electrical conductor cable 22, thru tubing 24. Tubing 24 is provided with valve means (not shown) for maintaining an air

tight seal around the cable. Movement of the cable up and down in the well is facilitated by pulleys 26 and 28 or by other suitable means.

An air line 30 connects with casing 14 below the well-head as shown or this line may pass thru the wellhead, similarly to tubing 24. A blower 32, or other suitable means, passes a stream of pressurized air thru line 30 into the well. A source of water under pressure, such as a tank 34, is connected with the well either directly or thru line 30 by means of line 36 containing motor valve 38. Water is admitted to tank 34 from line 40 as needed and pressurizing gas is passed into tank 34 thru line 42.

A temperature controller 44 is connected with cable 22 and with motor valve 38. This instrument (44) is set to maintain a suitable well temperature as sensed by thermocouple 18, such as not exceeding 300 or 400° F., depending upon the spontaneous ignition temperature of the adjacent stratum.

It is also feasible to utilize a series of vertically spaced spaced apart thermocouples such as 18, 46, and 48 in fixed or vertically adjustable position within stratum 10. In this arrangement, the maximum temperature sensed by the series of thermocouples actuates temperature controller 44 which operates valve 38 to introduce dispersion of water into the injected gas.

The apparatus of FIGURE 1 is used to prevent spontaneous combustion in well 12, particularly, in the adjacent stratum, during pressuring of the stratum prior to establishing in situ combustion in the stratum or during use of this well to inject air to a combustion front moving toward said well.

In FIGURE 2, a high-pressure water line 50 containing flow control valve 52 leads into air line 30 and is positioned so as to direct water onto a hemispherical solid surface 54 on device 56. This arrangement of apparatus assures the formation of a very finely divided water mist which is carried by the injected air into the well.

In FIGURE 3, a steam line 58 leads thru casing 14 into the path of the injected air and is provided with a flow control valve 60. This embodiment of the apparatus and process bleeds steam into the injection air to provide water droplets needed to maintain control of the temperature of the stratum in the well.

It is sometimes necessary to utilize an air injection pressure of several hundred to 1000 p.s.i.g. or more and it is, of course, essential to have available water pressure well above the air injection pressure. In such cases the steam pressure in line 58 and the water pressure in lines 50 and 36 must be adequate to effect injection and dispersion of the water against the pressure within the air line or well.

The water aerosol or mist is injected continuously in small quantities or intermittently in larger quantities automatically or by hand operation of valve 38 or the corresponding valves in the other embodiments of the apparatus. The quantity of water to be introduced varies from about an ounce to 10 or more pounds 1,000 standard cubic feet of gas, depending on the affinity of the reservoir hydrocarbon for oxygen, the injection pressure, and the nature of the emergency involved. Native petroleum and bitumens vary greatly in their oxygen affinity, i.e., their tendency to ignite spontaneously. Heavy crude from Kern County, California, exhibits an oxygen demand of the order of 1,000 times as much as some typical Missouri bitumens. Such crude definitely tends to ignite spontaneously upon prolonged exposure to high pressure air and, as previously pointed out, spontaneous ignition actually did occur during preliminary air injection operations on a recent underground combustion field test in the South Belridge field. While some crudes and bitumens exhibit far less tendency to ignite spontaneously than the Kern County example, it is good insurance to have available in all underground combustion operations means for injecting finely dispersed water into the injection gas.

It might be well to note that the combustion front can itself tolerate small quantities of well-dispersed water, so that injection well bores can thus be kept cool without extinguishing the counterflow combustion front. The preferred and most advantageous cooling fluid is H_2O in liquid form and/or steam form, but other coolants inert in the well bore ambient and readily separable from the production effluent may be utilized. Such coolants include N_2 , CO_2 , combustion gases, etc. The ensuing description of the invention will be limited to H_2O as the coolant but it is to be understood that other coolants may be utilized, even tho less advantageously.

Referring to FIGURE 4, a borehole 70, spaced from well 12 of FIGURE 1, penetrates carbonaceous stratum 10 and is provided with a casing 72, extending from ground level to the upper level of the stratum, and with production tubing 74, extending from adjacent the lower end of the casing through well head 76 to separating means 78. Line 80 carries water from separator 78 to waste or to recycle to the process as desired. Line 82 carries recovered hydrocarbons to refining or storage facilities.

A water line 84 extends to a level in casing 72 adjacent the lower end of tubing 74, or to a lower level within stratum 10, and is provided with a spray head or nozzle 86. Water line 84 passes through well head 76 and connects with a supply source, such as water tank 88. A pump 90 is inserted in line 84 for providing the desired pressure at spray head 86. Motor valve 92 is positioned in line 84 downstream of pump 90. Thermocouple 94, positioned in the well adjacent or below the lower end of production tubing 74 and preferably just above the level of spray nozzle 86, is connected with a temperature-recorder-controller 96 which is in operative control of motor valve 92.

Instruments 44 and 96 are conventional temperature-recorder-controller devices which are available from several sources. The Brown Instrument Company, of Philadelphia, Pa., is a supplier of this type of instrument which is illustrated in their Bulletin No. 15-4, copyrighted in 1942. Similar temperature-recorder-controllers are illustrated in "Principles and Methods of Telemetering," by Borden et al., Reinhold Publishing Corporation, 330 W. 42nd St., New York 18, New York, copyrighted 1948. Chapter 13 of this publication at page 184 illustrates one type of instrument suitable for the instant application.

At the stage of the process illustrated in the drawing, the fire front 98 has advanced from borehole 70 through the stratum a substantial distance toward surrounding air injection boreholes such as borehole 12 of FIGURE 1. The product hydrocarbons pass through the burned out area intermediate fire front 98 and borehole 70 to the borehole and into production tubing 74 in conventional manner. Fire front 98 eventually progresses to the injection boreholes and upon arrival, with continued air injection, the front is reversed in direction and is driven back to borehole 70 by direct air drive, feeding upon the carbonized residue left in the stratum during the inverse air injection phase of the process.

During the inverse air injection phase of the process, the hydrocarbons produced in and around fire front 98 by the heat of the combustion process and the flushing action of the combustion gases, principally in vapor form, pass into the borehole 70 at elevated temperatures around 1000° F. and sometimes as high as 1500 or 1600° F. In this type of in situ combustion, the produced hydrocarbons passing through the hot burned out zone back of the combustion front, together with O_2 which by-passes the fire front, appear in admixture in the production borehole and the temperature of the mixture sustains combustion, so that all of the oxygen present in borehole 70 consumes hydrocarbons and to that extent destroys valuable products, as well as contributing to excessive temperatures and damage to downhole equipment.

During the direct drive of the combustion front from the injection wells back to the production well, the front travels through the still hot burned out stratum and bypassed oxygen is again present in production 70 in admixture with hot hydrocarbons thereby causing borehole fires. The present invention prevents borehole fires or, if a borehole fire develops, the process can be utilized to extinguish the same and prevent the occurrence of further borehole combustion.

In operation of the invention, water is sprayed into the borehole, preferably, under substantial pressure such as 30 to 90 p.s.i.g., through a downhole spray, such as spray 86, so as to maintain the temperature in the borehole in the stratum below combustion supporting temperature at the concentration of oxygen in the borehole. It has been found that borehole fires do not occur when the temperature of the borehole is maintained below about 750° F. and it is preferable to control the injection of water into the borehole so as to maintain the temperature in the range of about 600 to about 700° F., although temperatures as low as 500° and as high as 750° F. have been used successfully. At higher temperatures, particularly at higher concentrations of oxygen, fire develops in the borehole and destroys valuable hydrocarbons being produced. As the temperature in the borehole drops below about 500° F., liquid products accumulate in the bottom of the borehole and water injected into the borehole forms an emulsion therewith which greatly complicates the separation problem in separator 78. In addition, at lower borehole temperatures the water-hydrocarbon emulsion in the bottom of the borehole is agitated by the flow of gases into the borehole and considerable erosion of the borehole wall below casing 72 occurs, with substantial amounts of sand and eroded material from the borehole appearing in the production effluent, further complicating the separation process. In other respects, at temperatures below 500° F., the process is just as effective in preventing borehole fires and preserving valuable hydrocarbons, but operation in this manner introduces other problems and disadvantages to the process which are undesirable.

While it is preferred to inject water in the manner shown in the drawing it has also been found effective to merely spray or otherwise inject water into the mouth of the borehole at ground level, whereby the water descends by gravity into the hot downhole section of the borehole where it effectively cools the production effluent so as to prevent the combustion of hydrocarbons with bypassed oxygen and thereby avoids well bore fires.

A preferred method of operation comprises sensing the temperature adjacent the upper level of the stratum being produced by means of thermocouple 94, or other temperature sensing device, which is connected with a temperature-recorder-controller 96 which in turn is connected with motor valve 92 and thereby controls the opening of this valve so as to inject the required amount of water into the borehole to maintain the temperature below the set temperature of instrument 96. While this is the preferred method of operating the process, hand operation of a flow control valve in line 84 in response to a sensed temperature in the well bore adjacent the producing stratum has been found satisfactory in a number of well tests. It is not necessary that the injection of water be continuous, as intermittent injection of water has been successfully tested.

Field tests in inverse air injection in situ combustion in a tar sand of substantial thickness at a level between 50 and 80 feet below the surface extending over a period of several months have been completed utilizing injection of water into the production boreholes at various levels in the well bore both intermittently and continuously. The injection of water in the manner described was found to be completely effective in eliminating borehole fires when the temperature was maintained below the range of 700 to 750° F. It was found that when as low

a concentration of oxygen in the production well bore as 0.5 volume percent occurred, the temperature in the well bore rose from about 1000° F. to the range of 1500 to 1600° F., without injection of water into the borehole, and with an oxygen concentration of only 3.0 percent, the temperature rose to at least 2500° F. Oil production without borehole combustion was sustained in some of these tests in which as much as 90 percent of the injected air bypassed the fire front and where the non-condensable effluent gas contained more than 18 percent oxygen. It was surprising that the critical maximum borehole temperature was as high as the range of 700 to 750° and that operation at borehole temperatures below about 500° F. was so undesirable because of complicating problems resulting therefrom.

A preferred method of initiating in situ combustion in and around the ignition or production borehole in an inverse burning process comprises heating the wall of the borehole within the carbonaceous stratum to ignition temperature and, while at this temperature, passing air thru the stratum into the borehole from one or more surrounding injection boreholes so as to initiate combustion of the carbonaceous material in the stratum. Thereafter, continued passage of air thru the stratum to the ignition borehole causes the resulting combustion zone or front to move thru the stratum countercurrently to the injected air. It is advantageous to incorporate a small percent fuel gas, such as 1 to 2% propane, with the injected air while initiating in situ combustion.

While the simplest method of injecting water into the hot production borehole within the stratum is thru a water line leading into the borehole and, preferably, to a level just above the stratum, it is also feasible to inject water into the borehole, or its wall, from one or more boreholes in the stratum within a short radius, such as one to several feet from the production borehole. Water injected in this manner into the wall of the production borehole has the beneficial cooling and diluting effect but requires drilling extra boreholes and is less desirable for this reason.

While the foregoing description of the invention is limited to fluid coolants, it is feasible to use readily vaporizable solid coolants such as particulate, solid CO₂ (Dry Ice) or ordinary ice, although the problem of introducing these materials to the well bore is a factor to be considered which makes injection of liquid H₂O or gaseous CO₂ preferable.

It has been found in inverse air injection field tests that the rate of air injection must be at least about 20 standard cubic feet per square foot of combustion front per hour in order to sustain a combustion front moving inversely to the air flow. When the air injection rate is reduced below this minimum, the combustion front is either reversed in direction, so as to turn back to the production borehole, or the fire goes out. The upper limit of the air injection rate depends upon economic factors such as compressor loss consumption of valuable hydrocarbons in the stratum and the character of the carbonaceous stratum itself; however, air rates of about 50 standard cubic feet per square foot of fire front per hour are marginal and can be economically utilized, while air rates of 100 s.c.f.h. per square foot of fire front are generally uneconomical and are maximum in any type of stratum.

Certain modifications of the invention will become apparent to those skilled in the art and the illustrative details disclosed are not to be construed as imposing unnecessary limitations on the invention.

I claim:

1. Apparatus for controlling temperature in a cased injection well used in an in situ combustion process which comprises in combination:

- (1) at least one temperature sensing device in said well adjacent a pay zone therein;
- (2) a conduit leading thru the casing of said well for

injecting O₂-containing, combustion-supporting gas;
 (3) means for injecting said gas thru said conduit;
 (4) a supply of water under pressure;
 (5) a line leading from said supply into said well thru
 said casing for injecting water into said gas;
 (6) a motor valve in said line;
 (7) means actuatable connected to said temperature
 sensing device and responsive thereto for opening
 said motor valve when the temperature adjacent said
 temperature sensing device reaches a predetermined
 value; and
 (8) means for raising and lowering said temperature
 sensing device within said well during gas injection.

2. The apparatus of claim 1 wherein a plurality of
 temperature sensing devices are positioned in vertically
 spaced-apart arrangement within the portion of well within
 said pay zone for sensing temperatures at different
 levels therein, said temperature controller being actuated
 by the maximum temperature sensed by said devices.

3. Apparatus for preventing well fire in a well in use
 in an in situ combustion process which comprises in combination:

- (1) temperature sensing means in said well adjacent
 an oil-bearing stratum for sensing temperature
 therein;
- (2) means for lowering and raising the means of (1)
 in said well;
- (3) a tubing extending thru the well head into said
 well;
- (4) an injection line for coolant communicating with
 said well;
- (5) flow control means in the line of (4); and
- (6) means responsive to the temperature sensing means
 of (1) in operative control of the flow control means
 of (5) for opening said flow control means when the
 temperature adjacent said sensing means reaches a
 predetermined value and controlling flow of coolant
 to substantially maintain a set temperature in said
 well adjacent the sensing means of (1).

4. The apparatus of claim 3 wherein the injection line
 of (4) extends to the level of said stratum and including
 a spray head on the lower end thereof.

5. The apparatus of claim 3 wherein said well is a
 production well in a reverse drive in situ combustion op-
 eration, the tubing of (3) is a production tubing, and
 the injection line of (4) is a water line.

6. Apparatus for controlling the temperature in a well
 penetrating a stratum undergoing in situ combustion com-
 prising in combination:

- (1) temperature sensing means in said well for sensing
 temperature therein;

5
 10

(2) means for lowering and raising the means of (1)
 in said well;
 (3) an air injection line communicating with said well
 for injecting air therein;
 (4) an injection line for water communicating with
 the line of (3);
 (5) flow control means in the line of (4); and
 (6) means responsive to the temperature sensing means
 of (1) in operative control of the flow control means
 of (5) for opening said flow control means when the
 temperature adjacent said sensing means reaches a
 predetermined value and controlling flow of coolant
 to substantially maintain a set temperature in said
 well adjacent the sensing means of (1).

7. The apparatus of claim 6 including water dispersing
 means in the line of (3) adjacent the delivery end of the
 line of (4).

8. Apparatus for controlling the temperature in a well
 penetrating a stratum undergoing in situ combustion com-
 prising in combination:

- (1) a plurality of temperature sensing devices posi-
 tioned in vertically spaced-apart arrangement within
 the portion of well within said stratum for sensing
 temperatures at different levels therein;
- (2) a conduit leading into said well for conduction of
 gases;
- (3) a supply of coolant under pressure;
- (4) a coolant line leading from the supply of (3) into
 said well for injecting coolant thereto;
- (5) a motor valve in the line of (4); and
- (6) means actuatable connected to the temperature
 sensing devices of (1) and responsive to the maxi-
 mum temperature sensed by said devices for open-
 ing the motor valve of (5) when the maximum tem-
 perature adjacent said stratum sensed by said devices
 reaches a predetermined value.
